UNITED STATES PATENT OFFICE.

BENJAMIN O. SWAIN AND JOHN S. TIMMONS, OF PHILADELPHIA, PENNSYLVANIA.

DEVICE FOR REDUCING THE INSULATING-STRIPS OF COMMUTATORS.

1,116,158.

Specification of Letters Patent.

Patented Nov. 3, 1914.

Application filed April 14, 1914. Serial No. 681,511.

To all whom it may concern:

Be it known that we, BENJAMIN O. SWAIN and JOHN S. TIMMONS, citizens of the United States, residing in Philadelphia, Pennsylvania, have invented certain Improvements in Devices for Reducing the Insulating-Strips of Commutators, of which the following is a specification.

This invention relates to a machine for reducing the height of sheets of mica, or other hard, non-resisting, insulating material, which are placed between the segments of a commutator. It is now found necessary to reduce, from time to time, the .5 sheets of mica as the commutator segments wear, so that the mica will always be below the surface of said segments.

One object of this invention is to provide a simple and effective machine for 20 cutting the mica separating strips and to provide an accurate machine, so as to prevent the saw or milling tool from cutting into the side walls and destroying the commutator segments.

25 A further object of the invention is to provide a device of the character above described which can be firmly held in the hand and which can be properly guided over the face of the commutator.

30 A still further object of the invention is to provide means for removing the mica dust from the groove as the cutting proceeds.

These objects and other advantageous ends 35 we attain in the following manner, reference being had to the accompanying drawings in which:—

Figure 1, is a perspective view illustrating our improved device for cutting the 40 insulating strips of commutators, one of the handles being broken away; Fig. 2, is an inverted plan view; Fig. 3, is an end view; and Fig. 4, is a longitudinal sectional view on the line $a-a$, Fig. 2.

45 Referring to the drawings, 1 is the body of the cutting device made of a block of metal, preferably of sufficient weight to retain it in position when the cutter is acting.

2, 2 are the handles, one secured to each 50 side of the body, as shown, and located near the forward end.

The body is slotted at 3, 3 at each side and the slot is preferably undercut as shown.

4, 4 are blocks adapted to the slots. 55 Projecting from each block is an arm 5 at the outer end of which is a runner 6

extending parallel with the body 1; these runners can be of any length desired.

By adjusting the blocks vertically in the slots 3 the device can be properly adjusted 60 with respect to a commutator of a given diameter so that the saw or milling tool 7 will make a cut of the proper depth. This is clearly illustrated in Fig. 3, the runner 6 bearing upon the commutator on each side 65 of the center, as shown.

Mounted on a projection 8 at the forward end of the body 1 is a spindle 9 located in an extended bearing 10. This spindle carries the circular saw or milling tool 7 at 70 one end and is shaped at the opposite end to receive the coupling of a flexible shaft, in the present instance. Other means of driving the spindle may be resorted to without departing from the essential features 75 of the invention.

The body 1 has a slot 11 in its underside extending its full length in line with and of a greater width than the saw or milling tool 7, and mounted in this slot are narrow 80 guide wheels 12, which rotate freely on spindles 13. These wheels are in line with the saw 7 and do not project so deeply into the kerf as the saw.

When the device is moved over an armature, the saw makes the first cut and then the wheels follow the saw, keeping the saw in alignment as the cutting proceeds, which facilitates the guiding of the machine and prevents the saw from cutting into the side 90 walls of the metallic segments.

In order to prevent the dust from accumulating in the grooves, we form a passage 14 in the body and connect an inclined nozzle 15 with this passage; the nozzle being in 95 line with the rear of the saw. The passage 14 is coupled to a pipe 16, which is attached to any source of air supply by a hose.

The operation is as follows:—The guiding runners are adjusted according to the 100 diameter of the armature to be cut so as to regulate the depth of the kerf made by the saw. Then the tool is grasped in both hands and, as the saw rotates, it is fed slowly into the space between the two segments of the commutator, cutting down the mica strip to a depth below the surface of the commutator. As the device is fed forward, the first guide wheel enters the groove and then the second guide wheel, which 105 guide the saw or milling tool in a straight course. When the cut is completed the tool

is lifted off the work and is adjusted to the next space.

By the use of this tool the armature need not be removed from the dynamo or motor, 5 and there is no complicated mechanism for attaching or locating the parts one in respect to the other to make the proper cut.

By having the two handles and the body of sufficient weight, an operator can steady 10 the work and can hold it in the proper position, and when the guide wheels enter the groove they prevent any swerving action of the cutter, which would injure or destroy the segments of the commutator.

15 In some instances, a single guide wheel may be used instead of the two wheels shown, or a single fixed guide may be located within the slot, which will enter the groove made by the saw so as to keep the saw in alignment.

20 Other means of driving the spindle may be resorted to without departing from the essential features of the invention, and, in some instances, the spindle may be driven 25 from an electric motor carried directly by the body portion; the spindle being geared to the armature shaft in any suitable manner, and, when a motor is mounted on the body portion, a fan may be used for removing 30 the dust from the kerf, taking the place of the air pressure hose.

We claim:—

1. The combination in a device for reducing the height of an insulating separating strip of a commutator, said device consisting of a body portion; a rotating cutter 35 mounted thereon; and a guide back of the cutter arranged to travel in the kerf made by the cutter.

40 2. The combination in a device for reducing the height of the insulating separating strip of a commutator, said device con-

sisting of a body portion; a rotating cutter; and a guide wheel back of the cutter.

3. The combination in a device for reducing the height of the insulating separating strip of a commutator, of a body portion; a transverse shaft mounted at one end of the body portion; a saw mounted on the shaft; a guide back of the saw; guides on each side of the body portion; a vertically adjustable runner adapted to each guide, the horizontal portion of the runners extending beyond the end of the saw; and handles by which the tool is manipulated. 55

4. The combination of a body having a longitudinal slot in its underside and a projection at the forward end at one side of the slot; a horizontal shaft mounted in the projection; a saw or milling tool mounted on the shaft in line with the slot; guide wheels mounted in the slot in line with the saw; and vertically adjustable runners secured to the body portion at each side. 60

5. The combination of a body portion 65 having a handle at each side; a shaft mounted on the body portion; a saw or milling tool mounted on the shaft, the body portion having a slot in its underside in line with the saw; a guide in the slot; runners secured to the body portion; and an air blast passage in the body portion having a nozzle in line with the saw so that the dust caused by the cutting will be removed as the tool travels. 70 75

In testimony whereof, we have signed our names to this specification, in the presence of two subscribing witnesses.

BENJAMIN O. SWAIN.
JOHN S. TIMMONS.
